United States Patent Office.

S. F. MATHEWS, OF MECHANICSBURG, PENNSYLVANIA.

Letters Patent No. 78,805, dated May 26, 1868.

IMPROVED GAS-REGULATOR.

The Schedule referred to in these Letters Patent and making part of the same.

TO ALL WHOM IT MAY CONCERN:

Be it known that I, S. F. MATHEWS, of Mechanicsburg, in the county of Cumberland, and State of Pennsylvania, have invented a new and improved Gas-Regulator; and I do hereby declare that the following is a full, clear, and exact description thereof, which will enable those skilled in the art to make and use the same, reference being had to the accompanying drawings forming part of this specification.

The object of this invention is to provide means of governing and controlling the flow of gas from the main pipe in a house before it is distributed to the burners.

And it consists in arranging an adjustable thimble on the end of a gas-pipe nipple, the position of which thimble is regulated by the pressure of the gas, and determines the quantity which is allowed to flow through to the burners, as will be hereinafter more fully described.

The drawing represents a longitudinal section of the apparatus, showing the parts of which it is composed, and the manner of their arrangement.

A is the body of the governor, containing the nipple-tube.

B is the nipple-tube.

C is the case, which screws into the governor A, forming a gas-chamber, D.

E is a thimble, which slides over the end of the nipple-tube so as to freely play thereon, but the extent of its movement is controlled by the screw f, which works in a slot in the tube B.

g is an orifice through the thimble E, which corresponds in size with an orifice in the tube B.

h is a spiral spring, attached to the thimble by the screw i, and to the governor A.

The power of this spring is barely sufficient to draw back the thimble when the pressure of the gas diminishes, after having extended it.

The pressure of the gas acts against the head of the thimble at j.

When the gas flows to the burners under the desired pressure, the orifices at g will correspond or register, as seen in the drawing.

Should the pressure increase, the thimble will be forced outward on the tube, and the orifice in the thimble will pass from or over the orifice in the nipple-tube, and the aperture for the discharge of the gas will be diminished in size accordingly.

The stop-screw f will prevent the thimble from entirely cutting off the gas.

When the pressure of the gas diminishes, the tension of the spring will draw the thimble back to its first position.

No gas can escape into the chamber D, except through the aperture g, and as the size of this orifice is governed entirely by the pressure of the gas, it will be seen that the instrument is a perfect regulator of the flow, and consequently the result is a great saving in the consumption of gas.

Having thus described my invention, I claim as new, and desire to secure by Letters Patent—

1. The nipple-tube B and the thimble E, constructed, arranged, and operating substantially as and for the purposes described, in combination with a gas-pipe.

2. The body of the governor A, the case C, tube B, thimble E, and spring h in combination, forming a gas-regulator, substantially as shown and described.

The above specification of my invention signed by me, this 21st day of February, 1868.

S. F. MATHEWS.
